UNITED STATES PATENT OFFICE.

LOUIS RUBIN, OF PHILADELPHIA, PENNSYLVANIA.

DESIGN FOR BATHING-ROMPERS.

56,626.

Specification for Design.

Patented Nov. 16, 1920.

Application filed July 29, 1920. Serial No. 398,324. Term of patent 14 years.

To all whom it may concern:

Be it known that I, LOUIS RUBIN, a citizen of the United States, residing at Philadelphia, in the county of Philadelphia and State of Pennsylvania, have invented a new, original, and ornamental Design for Bathing-Rompers, of which the following is a specification, reference being had to the accompanying drawing, forming part thereof.

The figure is a perspective view of a bathing romper, showing my new design.

My ornamental design for a bathing romper 1 comprises the waist portion 2, belt portion 3 and trouser portion 4, said belt portion being connected to said waist portion and trouser portion by the upper and lower portions 5 and 6. The flap portions 7 extend from the neck 8 to the open crotch 9 and the parallel tapes 10 and 11 on the inner surface of the back 12 also extend from said neck portion to said crotch portion.

I claim:

The ornamental design for a bathing romper, as shown and described.

LOUIS RUBIN.
